Primary Examiner — Susan Bennett Hattan

Assistant Examiner — Janice Hallmark

(74) Attorney, Agent, or Firm — Larson & Larson, P.A.;
Frank Liebenow; Patrick Reid(57) **CLAIM**

I claim the ornamental design for a tobacco product holder, as shown and described.

DESCRIPTION

FIG. 1 is a front perspective view of the tobacco product holder showing my new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.
